TRAILER MOUNTED SPRAYER UNIT

Roy F. Broyhill, Dakota City, Nebr. 68731

Filed July 10, 1970, Ser. No. 23,905

Term of patent 14 years

Int. Cl. D23—01

U.S. Cl. D23—18

FIG. 1

FIG. 2

FIG. 3

FIG. 4

FIG. 5

FIG. 1 is a side view of a trailer mounted sprayer unit showing my new design,

FIG. 2 is a front view thereof,

FIG. 3 is a back view thereof,

FIG. 4 is a side view opposite to that shown in FIG. 1, and

FIG. 5 is a perspective rear view shown in its relationship to a power vehicle which is in broken line for illustration only.

I claim:

The ornamental design for a trailer mounted sprayer unit, as shown and described.
